UNITED STATES PATENT OFFICE.

FREDERICK A. BERGMANN, OF MERRICK, NEW YORK.

OIL CUP.

Application filed February 10, 1923. Serial No. 618,186.

To all whom it may concern:

Be it known that I, FREDERICK A. BERGMANN, a citizen of the United States, residing at Merrick, county of Nassau and State of New York, have invented certain new and useful Improvements in Oil Cups, of which the following is a specification.

The principal object of this invention is to provide a new and improved construction 10 in oil cups by means of which the feed valve may be secured and held in a plurality of adjusted positions in such a manner as to prevent displacement of the setting of the needle valve by vibration or by any accidental blows.

Another object is to so construct the means for adjusting the valve that any desired number of adjustments can be had and which adjustments can be arranged to produce an accurate predetermined rate of feed.

A further object is to provide a new and improved construction of an automatic closure for the filling hole of the oil cup.

For the accomplishment of these and such further objects as will hereinafter be apparent to those skilled in the art to which this appertains, the invention consists in the construction, combination and arrangement 30 of parts herein specifically described and illustrated in the accompanying drawings, wherein is shown a preferred embodiment of the invention, but it is to be understood that changes, variations and modifications 35 may be resorted to which fall within the scope of the claims hereunto appended.

In the drawings forming a portion of this specification:

Fig. 1 is a side elevation of an oil cup embodying my invention.

Fig. 2 is a central section on the line 2—2 of Fig. 3.

Fig. 3 is a top view, showing the filling hole closure in position to close the filling hole and

Fig. 4 is a view similar to Fig. 3, showing the filling hole closure in open position.

As shown in the drawings, the numeral 10 indicates the usual threaded stem or nipple 50 of the oil cup which is preferably integral with the cylindrical body portion 11 and is provided with a feed conduit 12, terminating at its upper end in a valve seat 13, for the needle valve 14.

The upper edge of the cylindrical body

portion 11 is slightly flared outwardly to provide a bead 15 about which the cover 16 is spun or crimped in such a manner as to be fixed with respect to the body portion 11.

The cover 16 is provided with a filling hole 17 and a filling hole closure 18 is pivotally mounted upon the needle valve stem 19 and is provided with a downwardly depending flange 20 which rests upon the cover 16 and serves to space the closure 18 from the cover.

Pivotally mounted between a pair of small lugs 21 projecting downwardly from the under face of closure 18, is a lever 22 having one of its ends formed into a semi-spherical plug 23 constructed and arranged to seat within the filling hole 17 and seal the same when the closure is rotated upon its pivot to bring the plug 23 and hole 17 into alignment. A small leaf spring 24 is inserted between the lever 22 and closure 18 to normally urge the plug 23 downwardly and a pin 25 is secured in the other end of lever 22 and projects upwardly through a suitable aperture in the closure 18 to provide a means for actuating the lever 22 to cause the plug 23 to be withdrawn from the filling hole 17 when it is desired to open or uncover same.

The closure is cut away as indicated at 26 and 27 to form a pair of re-entrant openings through which free access may be had to the filling hole 17 when the closure 18 is given a slight rotation in either direction from the position shown in Fig. 3. A pair of springs 29, 30 have their contiguous ends anchored as at 31 to the closure 18 and their other ends suitably anchored as at 32 to the fixed cover 16 so as to normally urge or hold the closure 18 in its central or closed position shown in Fig. 3.

The upper face of the closure 18 is provided with a plurality of spaced upwardly projecting pins 33, the heights of which are progressively increased preferably in a clockwise direction starting from the lower right hand pin shown in Fig. 3, and a sleeve 34, pivotally mounted upon valve stem 19 is provided with a radially extending arm 35 which projects outwardly over the pins 33 and is provided with a recess 36 adapted to neatly engage over any one of the pins to lock the arm against rotation. The upper end of the sleeve 34 is recessed as at 37 to receive a small washer 38 fixed to

the valve stem 19, which serves to retain the sleeve 34 upon the valve stem. A washer 39 is secured upon the valve stem 19 within the cylindrical body 11 and acts as an abutment 5 for one end of a spring 40, encircling the valve stem and having its other end in contact with the under face of cover 16, thus serving to normally urge the valve toward its seat and also to hold the recess 36 of the 10 arm 35 in engagement with a pin 33 when the valve has been adjusted to any of its open positions.

If desired, a slot may be cut into the side wall of the body portion 11 to receive a 15 piece of transparent material 41 so as to provide an inspection window and I prefer to use for this purpose one of the synthetic compositions of matter such as are used for electrical insulations but which are now constructed in such a manner as to be 20 transparent, impervious to oil, and are not as frangible as glass. The manner of securing this transparent material may obviously be varied as desired as long as oil tight 25 joints are secured. Likewise the form of the springs and their points of support may be varied and also the number and heights of the pins 33.

The operation of the device is as follows, 30 if it is desired to fill the cup with oil the pin 25 is depressed to withdraw the plug 23 from the filling hole 17 and the closure 18 is rotated in either direction against the action of the springs 29, 30, to bring the one 35 of the re-entrant portions 26 or 27 into alignment with the filling hole. The spout of an oil can is then inserted into the filling hole and after the cup is filled the oil can is withdrawn and the closure then springs back under 40 the influence of the springs to the closed position shown in Fig. 3, the plug 23 engaging hole 17 and acting as a stop to check the return movement of the closure and to hold it securely in the position shown in 45 Fig. 3.

To set the needle valve to the desired feeding position, the knurled sleeve is raised against the action of spring 40 and rotated to cause the recess 36 of arm 35 to engage one 50 of the pins 33, thus causing the valve 14 to be raised off its seat 13 to a distance equal to the height of the respective pin. It will be noted that if it is desired to close the needle valve that it is not necessary to rotate the sleeve 34 and arm 35 back to a certain 55 fixed or starting position as is common with devices of this character, but that the needle valve will be closed for any position of the arm 35 between any of the pins 33. If desired, the top face of the closure may have

punched or stamped thereon adjacent each pin, any suitable numerals to indicate either the amount of drops of oil per hour fed for each respective setting of the valve or any other suitable characters or symbols to indicate the progression of the height of the pins from the lowest to the highest. 65

As the pins 33 are secured upon the closure 18, the setting of the needle valve need not be disturbed whenever the closure is rotated for filling the cup. While I have shown the needle valve adjusting means as mounted upon a rotatable closure, it will be obvious that the pins 33 could be directly mounted upon the upper outer surface of 75 any oil cup and that any other form of a filling hole or closure could be used.

The pin 33 nearest to the projecting pin 25 in the counter clockwise direction Figs. 3 and 4 is preferably of sufficient height to 80 open the needle valve to a point where a substantially free flow of oil from the cup is allowed.

Having thus described my invention, what I claim as new and desire to secure by Letters Patent of the United States, is:

1. An oil cup having a fixed cover provided with a filling hole, a closure rotatably mounted on said cover, said closure having a plug pivotally mounted thereon adapted to engage within said filling hole, spring means to normally urge said plug towards said filling hole, and means to normally hold said closure in a position to cause said plug to engage said filling hole, said closure having a reentrant profile adapted to expose said filling hole when said cover is rotated against the action of said last named means. 95

2. An oil cup having a fixed flat cover provided with an unobstructed filling hole, 100 a level closure rotatably mounted on said cover and having a depending flange to provide a space between said closure and said cover, an arm pivotally mounted upon said closure within said space, said arm terminating in a plug adapted to engage within and seal said filling hole, resilient means contacting with said arm and cover to normally urge said plug towards said filling hole, a pin on said arm projecting through said closure, and a pair of divergent springs normally holding said closure in a position in which the plug is engaged with said hole, 110 said closure having a contour exposing said filling hole when said cover is rotated against the action of said springs. 115

In testimony whereof I have affixed my signature.

FREDERICK A. BERGMANN.
